LLC; Rachel Gilboy(57) **CLAIM**

The ornamental design for a child's egg shaped ride-in car, as shown and described.

DESCRIPTION

FIG. 1 is a perspective view of the child's egg shaped ride-in car with the car top half in an open position showing my new design;

FIG. 2 is a front elevation view thereof, with the car top half in a closed position;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.
